UNITED STATES PATENT OFFICE.

NEWTON BLADES AND LEONARD VICTOR MARKS, OF LONDON, ENGLAND, ASSIGNEES
TO THE STERLING TELEPHONE & ELECTRIC COMPANY LIMITED, OF LONDON, ENGLAND, A COMPANY OF GREAT BRITAIN AND IRELAND.

IMPULSE TRANSMITTER FOR AUTOMATIC TELEPHONE SYSTEMS.

Application filed March 1, 1927, Serial No. 171,894, and in Great Britain March 15, 1926.

This invention relates to impulse transmitters for use in automatic telephones for sending to an exchange groups of impulses corresponding to the digits to which the 5 transmitter is successively set by a subscriber.

The purpose of the invention is the production of an impulse transmitter by which the whole dialling operation shall be expeditedly carried out, but which it shall be beyond the power of the subscriber to accelerate or interfere with.

To this end the invention comprises an impulse transmitter in which the movement 15 of the finger plate operated by the subscriber is wholly independent of the impulse sending operation, said finger plate being set by the subscriber as rapidly as he pleases, and returning or being returned without affecting the impulse sender, and being rendered powerless to actuate the impulse sender further until the impulse sending operation determined by its last forward movement is completed.

25 In a preferred construction of the invention the impulse sender comprises a preferably spring actuated driver and an impulse mechanism which is operated by the driver during its return to the position of rest under the action of its spring, the operation being controlled by a governor; the driver is carried forward by the finger plate during forward movement of the latter, but the finger plate returns independently of the 30 driver under the action of a separate spring. In the position of rest the finger plate is locked by a spring catch which is released by the impulse sender on completion of the impulse sending. To ensure proper engagement of the catch means are provided for slowing down the finger plate as it nears the 35 position of rest.

This embodiment of the invention is illustrated in the accompanying drawings,

40 Figure 1 being a face view with part of the finger plate and cover broken away.

Figure 2 an edge view in median section.

Figure 3 a diagram illustrating the locking notion.

45 Figure 4 a detail.

The finger plate A is secured upon a hub B rotating in a bearing C in the casing D. Within the casing there is attached to the hub a return spring L fastened to the cas-

ing, and at its end the hub carries an arm 55 E. The end of this arm lies in the path of the end of a second arm G carried on a spindle F co-axial with the finger plate hub B. This spindle may carry the usual pawl (not shown) engaging (during return 60 movement) the ratchet wheel K of the impulse sending mechanism O, or may be associated with that mechanism to drive it in any usual fashion. The arm G and the pawl together with a spring (not shown) which 65 tends always to return them to initial position constitute the driver. On rotation by the subscriber the finger plate A sets the driver so determining the number of impulses which will be sent, and on release 70 returns, under the action of its spring L, faster than the driver G can return since the latter must carry with it the governor controlled impulse mechanism. If the return of the finger plate is accelerated by the 75 subscriber the driver and impulse mechanism are not thereby affected.

As there is a possibility of the subscriber beginning the dialling of a further digit before the driver G has returned, a spring 80 catch M bevelled on one side is provided in the path of the arm E of the finger plate hub. The arm rides over this catch and is locked in its initial position between the catch and an abutment H as seen in Figure 85 3. The driver arm G upon its return also presses back the spring catch M but does not ride past it (Fig. 1). The ends of the arms E and G are flush with one another so that when the finger plate is again turned 90 forward in contact with the driver arm it can pass the catch. To prevent a gap being worn between the catch engaging surfaces of the finger plate arm and driver arm, the catch engaging surfaces of the driver 95 arm instead of being flush with that of the finger plate arm may partly overlie it in the initial position.

To prevent the arm G striking the abutment H with sufficient force to rebound before the spring catch has engaged it the end of the movement of the arm may be braked or cushioned in any suitable way. As shown in Figures 2 and 4 a leaf spring P is provided in the casing D which the 100 arm E must depress to reach its initial position.

What we claim is:—

1. An impulse transmitter, comprising a driver, a finger plate adapted to engage and set said driver on forward movement and otherwise wholly independent of it, means for returning said finger plate independently of said driver, means for returning said driver, an impulse mechanism operated by said driver in its return, and means rendering said finger plate inoperative until the return of the impulse sender is complete.

2. In an impulse transmitter the combination with an impulse sender, of a finger plate adapted on forward movement to determine the extent of operation of said sender, a spring for returning said finger plate, a spring catch to engage said finger plate in the position of rest until the impulse sending is completed, and means for gradually arresting said finger plate as it nears the position of rest.

3. In an impulse transmitter the combination with an impulse sender, of a finger plate adapted on forward movement to determine the extent of operation of said

sender, a spring for returning said finger plate, a spring catch to engage said finger plate in the position of rest until the impulse sending is completed, and a leaf spring in the path of said finger plate adapted to be deflected by it on nearing the position of rest.

4. In an impulse transmitter the combination with an impulse sender operating during return to a position of rest, of a finger plate adapted to rotate said impulse sender forward and to return independently thereof, a spring catch, a member moving with said finger plate adapted to press back said catch and to be engaged thereby in the position of rest, and a member moving with said impulse transmitter also adapted to press back said catch, the catch engaging surfaces of said members overlapping in the resting position.

In testimony whereof we have signed our names to this specification.

NEWTON BLADES.
LEONARD V. MARKS.
